(57) **CLAIM**

The ornamental design for a modular system channel, as shown and described.

DESCRIPTION

FIG. 1 is a perspective view of the modular system channel;
FIG. 2 is a front elevational view thereof;
FIG. 3 is a rear elevational view thereof;
FIG. 4 is a top plan view thereof; and,
FIG. 5 is a bottom plan view thereof.

The right and left sides of the modular system channel are unadorned, and, therefore, not illustrated.

The phantom line showing of environment is for illustrative purposes only.
